(57) CLAIM

The ornamental design for a health assessment kiosk, as shown and described.

DESCRIPTION

FIG. 1 is a front, top and side perspective view of my design for health assessment kiosk;

FIG. 2 is a front elevation view thereof;

FIG. 3 is an elevation view thereof from the side opposite that in FIG. 1;

FIG. 4 is an elevation view thereof from the same side as in FIG. 1;

FIG. 5 is a plan view thereof;

FIG. 6 is a rear elevation view thereof; and,

FIG. 7 is a bottom view thereof.

The portions of the health assessment kiosk, shown in dotted lines do not constitute a part of the claimed design.
